CLAIM

The ornamental design for a security camera, as shown and described.

DESCRIPTION

FIG. 1 is a bottom perspective view of a security camera showing my new design;

FIG. 2 is a top plan view thereof;

FIG. 3 is a side elevational view thereof;

FIG. 4 is a bottom plan view thereof;

FIG. 5 a top perspective view thereof with the surface mount plate removed for ease of illustration;

FIG. 6 is a top plan view thereof; and,

FIG. 7 is a side elevational view thereof opposite that shown in FIG. 3.

The broken lines in the Figures are for illustrative purposes only and form no part of the claimed design.
